RUFFLE CURTAIN

Frederick S. Nichols, Melrose, Mass.

Application February 15, 1947, Serial No. 728,895

2 Claims. (Cl. 2-278)

1

This invention relates to curtains, and particularly reversible ruffled curtains. The present invention is a continuation in part of my Patent No. 2,472,956, dated June 14, 1949.

Curtain ruffles, and wide curtain ruffles in particular, tend to droop or fall uncontrollably and present an unsightly appearance. Their tendency to droop at the sides of the curtain usually makes it necessary to use more material in the body of the curtain. Another loss of material occurs at the top of the ordinary curtain because the top of the body portions has a sheath for the curtain rod, and the top ruffles lie below the level of this sheath. The ordinary construction heretofore used also interferes with the use of curtains in more than one position, so that the curtain does not have as long a life as it would if frequently reversed.

The curtain of my invention is provided with ruffles which will retain their desired shape, and is capable of being turned end-for-end without the lowermost end at any time having the appearance of a reversible curtain, i. e. without looking as though it were hung upside-down.

The ruffle of the curtain of my invention is reinforced. The pleats of the ruffle are interengaged with pleats of a reinforcement band and the interengaged pleats are secured to the curtain by stitching in such manner that the ruffle and reinforcing band are held in more or less loose interengagement for some distance from the stitches. The engaged portions reinforce the rest of the ruffle, which retains the shape imparted to it. The reinforced section of the ruffle is also slotted to form a curtain rod sheath, so that a curtain rod may be passed directly through the ruffle itself.

The invention will be more clearly understood from the following description in conjunction with the accompanying drawings, in which:

Fig. 1 is a fragmentary view of a curtain embodying the invention;

Fig. 2 is a section on line 2-2 of Fig. 1; and

Fig. 3 is a section on line 3-3 of Fig. 2.

In the drawings, the curtain body 10 is stitched with double rows of thread 12 to ruffle 14 having a skirt 16 and head 18 on opposite sides of the stitching 12. The material of the ruffle is pleated at the lines of stitching (Fig. 3). The skirt 16 is wider than the head 18, and is reinforced by a band 20 which is also pleated, so that the pleats are interengaged. They are tightly engaged at the lines of stitching, and loosely engaged for some distance into the skirt portion 16, unless subsequently separated.

2

In Fig. 2, ruffle 14 and band 20 are preferably made from a single piece of material, band 20 being formed by folding back part of the material of the ruffle. But whether made from a single piece 5 of material or from separate pieces, the band 20 is sewed to the skirt 16 by stitching 32. Between stitching 12 and stitching 32, at each of the four corners of the curtain, I make slits 34 which enable a curtain-rod to be passed through from one 10 side of the curtain to the other in the space formed between the band 20 and skirt 16.

The initial pleating and interengagement of band 20 and skirt 16 along the stitching 12, when no curtain rod is placed between them, will cause 15 mutual inter-folding outwardly toward stitching 32 and will enable the flaring skirt to stay in place. The inter-folding also makes the combined band and skirt portions blend to obscure the passage for the curtain rod. Thus when the curtain is hung, the bottom does not appear to have a sheath formed in it. When a curtain rod is placed in the sheath or space between band 20 and skirt 16, the mutually interfolded portions of the curtain tend to restrict the passage, and so 20 the material hugs closely about the curtain rod. Each fold provides resistance, and tends also to continue over and about the rod to stiffen the ruffled portion standing above it.

The improved curtain of the invention requires 25 less material, since the ruffle stands out and so a given window requires less curtain material for the body portion. Less body-forming material is required, also, because the body portion does not need to be folded over at the ends to provide curtain rod sheaths or passages. Further, the curtain rod is obscured by the pleated ruffle, and does not show nearly as much, while absence of the rod, at the end temporarily serving as the bottom of the curtain, allows the loose pleating to continue uninterrupted through the reinforced portion and conceal the presence of a passage through the material. The bottom of the curtain, in consequence, never appears as though designed for use only at the top. The reinforcement band itself does not appear to the eye as a reinforcement, but rather lends the ruffle a two-tone effect, as though the meshes were more closely spaced.

I claim:

1. A curtain comprising, in combination, a body portion, a ruffle skirt secured to said body portion, a reinforcing ruffle band of pleated material interengaged with pleats in said ruffle skirt, and slits in said reinforcing band to form a curtain rod sheath between said band and said skirt.

2. A curtain comprising, in combination, a body portion, a ruffle skirt, a reinforcing ruffle band, and slits formed at the corners of said ruffle skirt to form a sheath for a curtain rod between a folded portion of said reinforcing band 5 and a folded portion of said ruffle skirt.

FREDERICK S. NICHOLS.
